UNITED STATES PATENT OFFICE

ANTHONY VANDERVELD, OF GRAND RAPIDS, MICHIGAN, ASSIGNOR TO GRAND RAPIDS STORE EQUIPMENT CORPORATION, OF GRAND RAPIDS, MICHIGAN, A CORPORATION OF MICHIGAN

BRACKET

Application filed February 17, 1930. Serial No. 428,997.

This invention relates to brackets, and particularly to brackets of the type known as adjustable shelf brackets, which may be used in many places but which in practice are extensively used in supporting shelves in showcases, cabinets and other articles of store furniture. The brackets of this kind are adjustable by shifting the same to different positions in the lengths of vertical supporting posts which carry them and from which they project horizontally, and when connected to the supports at any particular places it is desirable that each bracket be secured to its post or other support therefor so that it will not accidentally or otherwise disengage therefrom.

It is a primary object and purpose of the present invention to provide a novel construction of shelf bracket and a novel means for securing it adjustably to a vertically positioned supporting post to which it may be connected, at any one of a large number of spaced apart points in the length of the post, means being used to securely clamp the bracket to the post after it is once located in place thereon so as to positively prevent disengagement of the bracket from the post until desired and only after the clamping securing means has been operated to disengage from the post. Other objects and purposes of the invention are to provide a construction having the advantages noted which is simple and easy to manufacture and assemble and one which may be produced at low cost.

Understanding of the invention for the attainment of the ends stated, as well as many others not at this time specifically enumerated, may be had from the following description, taken in connection with the accompanying drawings, in which,

Fig. 1 is a side elevation of the bracket of my invention connected to a post, shown fragmentarily, and supporting a shelf which is indicated in section.

Fig. 2 is a fragmentary enlarged elevation and section showing the end of the bracket which is engaged with the post clamped thereto by means of my invention, the post being shown in vertical section.

Fig. 3 is a fragmentary elevation and sec-

tion of the post engaging end of the bracket, the clamping device and the means for operating the same being shown in vertical section.

Fig. 4 is a plan view of the structure shown in Fig. 2.

Fig. 5 is a vertical section on the plane of line 5—5 of Fig. 2, looking in the direction indicated by the arrows, and

Fig. 6 is a fragmentary perspective view showing the post and the post engaging end of the bracket separated therefrom.

Like reference characters refer to like parts in the different figures of the drawings.

In the construction illustrated, a bracket arm 1 is made of flat metal, which arm in use is positioned in a vertical plane extending laterally from its post. Said bracket arm is ordinarily provided at its free end with an upwardly extending lip 2 to prevent the shelf, indicated at 3, from moving off the bracket beyond the free end thereof. The bracket arm is of greatest height at the end where it is to engage with the supporting post.

The supporting post may be of channel form having a face web 4 from which spaced flanges 5 extend at right angles, the web 4 being provided with a series of spaced apart elongated vertical slots 6, best shown in Fig. 6, the width of which is but slightly greater than the thickness of the metal from which the bracket arm is made.

The bracket arm 1, at its upper side and adjacent its post engaging end, has a shallow elongated recess 7 therein and directly at the end it is formed with two vertically spaced hooks 8 which are of a shape that they may pass readily through the slots 6, whereupon the arm as a whole may be moved downwardly a distance equal to the depth of the slots 8a between the hooks and the end of the bracket arm. The bracket arm, adjacent its post engaging end and near the lower edge thereof, has an irregularly shaped opening 9 therethrough which, as shown in Fig. 3, is narrowed at its upper end, has a substantially vertical side 10 and a lower horizontal side 11 leading outward to the edge of the bracket arm, while at its upper side it is of a curved

form, indicated at 12, and also leading as indicated at 13 to the outer edge of the metal from which the arm is formed, the two edges 11 and 13 defining an entrance slot into said opening.

5 A clamping member is located over and embraces the bracket arm adjacent the post engaging end thereof. It is formed from a single piece of metal bent into substantially 10 U-shape and including an upper connecting section 14 which is of a width at one end where it is to engage the post substantially equal to the width of the web 4 and is narrower at the other end (see Fig. 6). The edges 15 of the part 14 are bent inwardly and then extended downwardly to make parallel legs 15. This clamping member may be placed over the bracket arm 1 with one of the legs 15 at each side thereof, the recess 7 receiving the 15 upper connecting part 14 and said clamping member is pivotally connected to the arm by means of a pivot 16 which passes through the legs 15 and the bracket arm 1, the pivot being a short distance below the upper connecting section 14 as shown in Fig. 2. The lower ends of the legs 15 described extend to and slightly below the opening 9 in the bracket arm previously described.

20 An operating member for the clamping device is mounted on the bracket arm and comprises a U-shaped member made of a single piece of flat metal having a connecting section 17 from which legs 18 extend at right angles and parallel to each other. The connecting portion 17 of the operating member is located in the opening 9 and the legs 18 are spaced far enough apart that when turned to upper position, as shown in Fig. 2, the legs 15 of the clamping member are between 25 the sides of the bracket arm 1 and the legs 18 of the clamp operating member.

25 In attaching the shelf supporting bracket to the supporting post the hooks 8 are passed through any two adjacent slots 6 in the web 4, the operating member being in horizontal position as indicated in Fig. 6. This is the same position as shown in Fig. 3 and it will be noted that the part 17 at its upper edge is located in the upper narrower portion of the opening 9. After the bracket has been positioned on the post, the clamp operating member is turned from the horizontal position, shown in Fig. 6, to the vertical position shown in Fig. 2, whereupon the clamping member is turned about its pivot 16 due to the lower end of the part 17 (as shown in Fig. 3) coming against the edges of the legs 15 and causing them to be moved in a counter-clockwise direction, thereby bringing the edge of the wider end of the part 14 against the outer face of the web of the post. This causes a bite of the metal of the part 14 against the metal web 4 of the post thereby holding the clamp securely in connection with the post and positively preventing any upward move-

ment of the clamp or the bracket arm 1 to which it is attached.

70 The wider end of the part 14 is downwardly dished as indicated at 14a so that it will come against the upper edge of the bracket arm 1 within the recess 7 before the operating member 18 has been turned fully to the position shown in Fig. 2. The legs 15 of the clamping member have a sufficient measure of flexibility, however, that the same will spring a short distance to permit turning the clamping member to its proper position and will thereafter bear on the part 17 of the clamping member with pressure sufficient to hold the operating member securely in its operative position shown in Fig. 2.

75 The parts from which the bracket construction and the supporting post are made are readily manufactured from flat metal by means of dies very expeditiously and at low 80 cost. The assembly is simple, it consisting merely of introducing the cross connecting portion 17 of the clamp operating member into the opening 9 turning it to the position shown in Fig. 6, then placing the clamping member over the bracket arm and inserting the pivot 16 in place and riveting over the end of the pivot.

85 With this construction a secure connection of a shelf supporting bracket to its supporting post may be had yet the bracket may be adjusted to different positions in the length of the post. The slotted openings 6 in the post are reduced to a minimum in width and there is no necessity of using a key-hole or key slot as have been used frequently heretofore. The narrower slots present a greater improved appearance. The clamping member and the operating member therefor are located in an inconspicuous place and do not detract in any measure from the appearance of the structure. The release of a bracket from its post for adjustment is exceptionally quick and easy and is effected without the use of 90 tools of any description. These features combine to make the invention one of considerable practical merit and advantage. The invention is defined in the appended claims and is to be considered comprehensive of all 95 forms of structure coming within their scope.

100 I claim:

1. In a construction of the class described, a vertical supporting post having slots therein, a bracket arm having means at one end to enter said slots whereby the bracket arm 105 may be engaged with or disengaged from the post, clamping means mounted on said arm and positioned in front of the post and above the engaged slot and movable to engage and clamp against the post to hold the arm against movement with respect to the post, means mounted on the bracket arm for operating said clamping means to thereby move it either to an operative clamping position or to release it from engagement with the post.

2. In combination, a vertical supporting post having spaced apart narrow elongated slots located in vertical alignment, a bracket arm formed with spaced apart hook means at 5 one end to enter said slots, a clamping member pivotally mounted on said arm adjacent its post engaging end and extending downwardly alongside the arm, and operating means movably mounted on said bracket arm 10 for engaging with the clamping means to turn it to position to engage against the face of the post in which said slots are made.

3. In combination, a vertical post having a plurality of narrow elongated slots therein spaced from each other and located in vertical alignment, a bracket arm made from flat metal, downwardly extending hook members at one end of the arm to pass through said slots in the post and engage with the post, 15 a U-shaped member located over said bracket arm adjacent its post engaging end having depending legs extending downwardly at each side of the post, means pivotally mounting said clamping member on said bracket 20 arm adjacent the upper edge of the arm, and means movably mounted on the bracket arm adjacent the lower ends of the legs of the clamping member for turning the clamping member into operative position to engage 25 against said post.

4. A construction containing the elements in combination defined in claim 3, said operating member comprising a U-shaped stirrup of metal passing through an opening in 35 the bracket arm and adapted to be turned from horizontal to vertical position and vice versa to move the clamping member to operative clamping position and to release it from said position.

5. In a construction of the class described, 40 a vertical post of flat metal having a plurality of narrow elongated slots therein, said slots being located in vertical alignment and spaced apart, a bracket arm of flat metal 45 formed at one end with means to enter said slots and engage with the post, a clamping member formed from a single piece of metal bent into substantially U-shape and located over the bracket arm adjacent its post en- 50 gaging end, means for pivotally mounting the clamping member on said arm near the upper edge thereof, said arm having an opening near its post engaging end and near its lower edge, and an operating member formed 55 from a single piece of metal bent into U-shape extending through said opening to engage with the depending leg portions of said clamping member whereby on turning the operating member upwardly the clamping member is brought into operative clamping 60 engagement against said post.

6. A construction containing the elements in combination defined in claim 5, said opening in the bracket arm having a substantially 65 vertical inner edge, a horizontal lower edge

and a curved upper edge whereby the opening is of substantially triangular shape and the part of the operating member extending therethrough has a width whereby it engages against the curved edge of said opening when 70 in horizontal position and bears against the vertical edge of said opening when turned toward vertical position to thereby turn the clamping member about its pivot, the depending legs of said clamping member being sufficiently resilient to yield upon the clamping member engaging with the post before the operating member has been turned fully to vertical position.

In testimony whereof I affix my signature. 80
